UNITED STATES PATENT OFFICE.

WILLIAM V. BULMAN, OF PHILADELPHIA, PENNSYLVANIA.

MULTIPLE DIE-STOCK.

1,274,850.

Specification of Letters Patent.

Patented Aug. 6, 1918.

Application filed April 18, 1918. Serial No. 229,294.

To all whom it may concern:

Be it known that I, WILLIAM V. BULMAN, a citizen of the United States, residing at Philadelphia, in the county of Philadelphia and State of Pennsylvania, have invented 5 certain new and useful Improvements in Multiple Die-Stocks; and I hereby declare that the following is a full, clear, and exact description thereof, reference being had to 10 the accompanying drawings, which form a part of this specification.

This invention is an improvement in die stocks for use in threading pipes or bolts; and its object is to provide a stock adapted 15 to contain a number of dies, any one of which may be immediately brought into use by merely properly positioning the stock.

The advantages of the invention are the saving of expense by providing one die stock 20 which is capable of doing the work of four ordinary die stocks; the saving of time by providing four or more sets of dies in one head or stock, each ready for immediate use as desired; the saving of annoyance and 25 labor by mounting a number of sets of dies on one stock, to which they are securely attached and always ready for use, thus avoiding the frequent loss or misplacement of parts occasioned with the ordinary die 30 cutting outfits in which a series of detachable interchangeable dies are to be used with one stock, and each time that a different sized thread is to be cut one set of dies has 35 to be removed from the stock and the proper set of dies attached thereto.

My invention provides a simple, convenient and useful multiple die stock, and I will explain the same in detail with reference to the accompanying drawings which 40 illustrate one practical embodiment of the invention; which I do not consider restricted to the specific form or construction of parts illustrated in the drawings, and therefore refer to the claims for summaries of the essential characteristic features of the invention 45 for which protection is desired.

In said drawings:

Figure 1 is a top plan view of my multiple die stock.

50 Fig. 2 is bottom view thereof.

Fig. 3 is a front edge view thereof.

Fig. 4 is a longitudinal section on the line 4-4, Fig. 1.

Fig. 5 is a top plan view of the head with 55 all the dies removed.

The die stock is shown as adapted to

carry four sets of dies; two on one side and two on the other. The two sets of dies on each side of the stock are arranged parallel and separated by an intermediate spacing 60 rib; and the sets of dies and rib on one side of the stock are arranged at right angles to the sets of dies and rib on the opposite side thereof; and the rib at one side of the stock is provided with guide openings for 65 the rod or pipe to be threaded by the dies on the opposite side of the stock.

For the sake of explanation I will refer to the side of the stock shown in Fig. 1 as the upper side; and the side of the stock 70 shown in Fig. 2 as the underside of the stock. These two sides are substantially alike.

The upper side member 1 of the stock is approximately rectangular in plan and is 75 preferably formed or cast integral with the other parts of the stock; said side is provided with parallel guides or channels 1^a and 1^b for the reception of sets of dies D' and D² which are fastened to the top by 80 means of tap bolts 2 and 2^a and may be adjusted toward or from each other by means of tap bolts 2^b and 2^c tapped through end lugs 1^e and 1^d at the outer ends of the slots 1^a and 1^b respectively. The central 85 portion or rib 1^e between the guide channels is provided with perforations 1^f and 1^g for a purpose hereinafter explained.

The under side member 3 of the stock is substantially similar to the upper side 1 and 90 is parallel therewith and spaced therefrom but integrally connected therewith by end walls or members 5. The side member 3 is provided with exterior guides or channels 3^a and 3^b for the reception of sets of dies 95 D³ and D⁴, which are attached to side 3 by tap bolts 4 and 4^a, and which may be adjusted by means of bolts 4^b and 4^c tapped through lugs 3^e and 3^d on the member 3 at the ends of the slots. The intermediate portion or rib 3^e between the guide channels 100 is provided with perforations 3^f and 3^g.

It will be seen that the sets of dies D' and D² and intermediate rib 1^e of side member 1, extend at right angles to the sets of 105 dies D³ and D⁴ and intermediate rib 3^e of side member 3. The openings 1^f, 1^g in rib 1^e are respectively in axial alinement with the operative faces of the sets of dies D³ and D⁴; while the openings 3^f and 3^g in 110 the rib 3^e are respectively in axial alinement with the operative faces of the dies

D' and D²; so that to position the die stock on a rod or pipe to be threaded it is simply necessary to slip the end of the rod or pipe through the proper opening opposite the die which is to be engaged therewith. The side members 1 and 3 are the opposite sides of a block provided with suitable openings for the passage of the rods or dies, the inner portions of the block being cored out 10 for the purpose of lightness so as to practically separate the members 1 and 3; but all parts of the stock are preferably cast integral. To further strengthen the end members at the points where the bolts 2, 2^a 15 and 4, 4^a are engaged therewith I provide studs or web portions 6 with which the said tap bolts can be engaged.

The end walls 5 may be provided with projecting handle-portions or members 5^a 20 which may be interiorly threaded for engagement with handle rods 5^b of any suitable kind by which the stock can be rotated to cause any die to operate on the rod or pipe with which it is properly engaged.

All four sets of dies remain attached to the stock; and it is capable of performing the work of four ordinary die stocks. Each set of dies is preferably for a different 30 size of work, and any set of dies can be readily engaged with the work by merely properly positioning the stock.

What I claim is:

1. In a multiple die stock; opposite spaced 35 side members each having parallel die channels and a rib on its outer face; the channel and rib on one member extending at right angles to the channel and rib on the opposite member; dies in said channels; the rib on 40 one member having openings for positioning a rod or pipe in proper relation to the die on the opposite member.

2. In multiple die stock; opposite spaced 45 side members each having parallel channels for dies on its outer face and a spacing rib; the channels and ribs on one member extending at right angles to the channels and rib on the opposite member; and dies in each channel; the spacing rib on one member having openings for positioning a rod or pipe in proper relation to the dies on the opposite member.

3. In a multiple die stock; opposite spaced 50 members each containing parallel die chan-

nels on its outer face separated by an intermediate spacing rib; an adjustable set of dies in each channel; the channels and rib on one member extending at right angles to the channels and rib on the opposite member; and the spacing rib on one member having openings for positioning a rod or pipe in proper relation to the dies on the opposite member; and means rigidly uniting said side members and spacing them properly apart.

4. In a multiple die stock; opposite spaced side members each having parallel die channels and rib on its outer face, the channel and rib on one member extending at right angles to the channel and rib on the opposite member; dies in said channels; the rib on one member having openings for positioning a rod or pipe in proper relation to the die on the opposite member; end members rigidly uniting said side members and spacing them properly apart; and handle parts on said end members.

5. In a multiple die stock; opposite spaced side members each having parallel channels for dies on its outer face and a spacing rib, the channels and rib on one member extending at right angles to the channels and rib on the opposite member; dies in each channel; the spacing rib on one member having openings for positioning a rod or pipe in proper relation to the dies on the opposite member; studs rigidly uniting said side members and spacing them properly apart; and bolts adjustably securing the dies to the members and tapped into said studs.

6. In a multiple die stock; opposite spaced members each containing parallel guide channels on its outer face separated by an intermediate spacing rib or bar; an adjustable set of dies in each channel, the channels and rib on one member extending at right angles to the channels and rib on the opposite member; the spacing rib on one member having openings for positioning a rod or pipe in proper relation to the dies on the opposite member; studs rigidly uniting said side members and spacing them properly apart; bolts securing the dies to the members and tapped into said studs; and handles attached to said stock.

In testimony that I claim the foregoing as my own, I affix my signature,

WILLIAM V. BULMAN.
